UNITED STATES PATENT OFFICE.

FRANK ANTON EICH, OF ROCHESTER, NEW YORK, ASSIGNOR TO UNITED SHOE MACHINERY CORPORATION, OF PATERSON, NEW JERSEY, A CORPORATION OF NEW JERSEY.

METHOD OF AND MACHINE FOR SHAPING HEELS.

Application filed May 28, 1922. Serial No. 563,900.

To all whom it may concern:

Be it known that I, FRANK A. EICH, a citizen of the United States, residing at Rochester, in the county of Monroe and

5 State of New York, have invented certain Improvements in Methods of and Machines for Shaping Heels, of which the following description, in connection with the accompanying drawings, is a specification, like

10 reference characters on the drawings indicating like parts in the several figures.

This invention relates to heel-shaping and more particularly to shaping the periphery as distinguished from the breast of a heel.

15 For the purpose of considering certain problems with which the invention is concerned heels may be said to be divided into two classes, viz., those having a wedge formation and those having no such formation, or, 20 if any, only a negligible degree. The reason for thus classifying heels will appear in due course.

As a general rule men's and boys' heels, also some low heels for women's sport shoes, 25 have no wedge formation, or, if any, only a negligible degree thereof. A so-called wedge heel has greater height at the back than at the breast, in consequence of which the heel-seat line is inclined relatively to 30 the tread or toplift. Louis heels, military heels and Cuban heels are well-known examples of heels having pronounced wedge formation and are difficult styles to trim by methods heretofore practiced.

35 In shaping wedge heels by machinery the wedge formation has heretofore made it necessary to perform two separate shaping operations, by the first of which only that portion of the heel exclusive of the wedge portion has been shaped, and by the second of 40 which the wedge portion has been shaped simultaneously with what is termed a "randing" operation. In other words, in shaping by machinery a heel having a wedge formation it has always heretofore been necessary to restrict the first shaping to a range no greater than the lowest part of the heel and to shape the wedge or base portion by a subsequent operation. Without reciting all the 45 disadvantages of such two-step shaping two major disadvantages may be mentioned.

One is that the total time required for shaping a heel is about double, and the other and more serious one is that it is practically impossible to merge the second cut with the 55 first so smoothly as to avoid forming a ridge, angle or other irregularity that requires so much scouring that it cannot be eliminated without sacrificing the true shape and without devoting too much time to scouring.

60 In view of the foregoing and other conditions an object of the present invention is to provide for shaping the periphery of a heel entirely in one operation.

A feature of the invention consists in an 65 organization including a cutter-head, a movable counter guard, and a movable toplift guard, such that both guards may be moved relatively to the cutter-head and relatively to each other while a trimming operation is 70 in progress, and mechanism for controlling the movements of the guards however it may be necessary to do so to produce any desired shape. So far as I am aware no prior heel-shaping machine has been organized 75 as above stated. In most cases the toplift guard has been fixed and the counter guard has been displaceable by the work and urged toward it by a light spring, although for trimming spring heels, it has 80 been proposed to fix the counter guard and to provide a light spring to urge the toplift guard toward it so that the toplift guard may be displaced by the work.

85 Another object of the invention is to provide a heel-shaping machine that will be adaptable, in consequence of certain adjustments, in some cases with, and in other cases without, a change of cutters, to meet the requirements of all styles of heels so that 90 any heel, of whatever style, may be completely and satisfactorily shaped in one operation. In this respect a feature of the invention consists in certain novel features of construction and organization by which a heel-shaping machine may be quickly regulated to meet the requirements of any recognized style of heel. For example, in the use of the illustrated machine, the toplift guard and the counter guard may both be 95 fixed, or either one may be fixed and the other one moved toward and from it, or 100

either one may be controlled in such a way that it will have a relatively slight movement while the other may have a greater range of movement. Also, either or both guards may be adjusted and fixed or movably controlled to utilize any desired part of the cutter and to cover those parts that are not suited to the particular requirements in any case. In this way certain parts of the cutter may be covered and uncovered by one guard or the other or by both, as the case may be, while a trimming operation is in progress. This feature not only renders the machine universal for all styles of heels but affords a considerable variety of shapes from a single set of cutters and provides for taking care of all recognized styles with only three or four sets of cutters.

Another object of the invention is to provide an improved construction by which the entire thickness of the toplift may be trimmed while the body of the heel is being trimmed. The usual practice is to use the toplift as a templet to determine a course of trimming, but heretofore a considerable portion of the thickness of the toplift has been maintained out of contact with the trimming cutter by the guard with which it cooperates. In consequence of such practice it has been necessary subsequently to complete the trimming of the toplift by scouring, and for some styles also to reduce the body of the heel considerably by scouring. This is objectionable not only because of the time required for the scouring operation but also because it is practically impossible then to preserve the desired profile and contour imparted by the shaping cutter.

In the latter aspect the invention provides an improved organization including a novel toplift guard by virtue of which the entire thickness of the toplift may be subjected to the trimming action of the cutters while the other parts of the heel are subjected to such action, without sacrificing in any degree the utilization of the toplift as a templet for determining the course of trimming. An advantage of this feature is that the degree of scouring necessary to finish the surface is so slight that the shape imparted by the shaping operation may be substantially preserved. The finished work may therefore be substantially identical in contour as well as in profile with predetermined standards, and uniformity is assured.

Other objects of the invention are herein-after described and other features are herein-after described and claimed and are illustrated by the accompanying drawings.

60 Referring to the drawings,

Fig. 1 is a top plan view of a machine organization embodying one form of the present invention;

65 Fig. 2 is a diagrammatic view similar to Fig. 1 showing some of the principal ele-

ments in successive positions that would be appropriate in the course of shaping one style of heel;

70 Fig. 3 is a diagrammatic view showing one style of Louis heel in various positions in operative relation to a rotary shaving cutter by which its could be completely shaped in one operation, and indicates various extents to which the profile of the cutter would be utilized at the various stages of shaping; 75

Fig. 4 is a perspective view including the shaving cutter, the toplift guard and the mechanism by which the latter may be shifted and controlled as occasion may require; 80

Fig. 5 is an elevation partly in section of the mechanism at the right of line 5-5 of Fig. 1;

85 Fig. 6 is a front elevation of the mechanism included in Fig. 1;

Figs. 7 and 8 are diagrammatic views including side elevations of typical examples of heels having wedge factors.

90 The elements included in Fig. 1 occupy their normal or initial positions although no attempt has been made in this figure to represent adjustments for any particular operation or style of heel. The purpose of this figure is to illustrate a suitable form of mechanism without special regard to any particular adjustment of the adjustable elements for any predetermined conditions. For example, the counter guard hereinafter described is not adjusted so closely to the shaving cutter as it would ordinarily be 100 under operative conditions but the mechanism includes adjusting means by which its desired relation to the cutter may be readily established. A rotary cutter head including detachably clamped cutters 10 is carried by a shaft 11 mounted in suitable stationary bearings one of which is indicated at 12. No driving mechanism for the cutter shaft is illustrated since any suitable or well-known driving mechanism may be used. The illustrated cutters have a profile suitable for 110 trimming a Louis heel and other styles, depending upon the extent to which and the manner in which the counter guard and toplift guard are positioned and controlled as 115 hereinafter described. In accordance with well-known practice the cutters 10 may be replaced by cutters of other profile so that the machine may be used to shape all recognized styles of heels. For example, instead 120 of using the illustrated cutters which have a profile characterized by an ogee curve, cutters having a simple curve or cutters having a straight profile may be substituted. Three sets of cutters having the characteristics 125 above mentioned would be sufficient, according to the possibilities of this invention, to shape nearly if not quite all the recognized styles of heel, although some manufacturers might prefer to supplement such equipment 130

of cutters by another set having a similar curve of a different degree of curvature.

The toplift guard, which is shown best by Figs. 4 and 5, embodies novel features of construction and is controlled as to position by novel mechanism, each of which novel aspects contributes a novel result to the shaping of a heel. There are three principal parts to the toplift guard, including a tread-engaging member shown in the form of a block 13, and two cooperative abutment members 14, 14 spaced apart one from the other and arranged to engage the periphery of the toplift. The members 14 are so positioned relatively to the shaving cutter that the latter may shave the entire thickness of that portion of the toplift that bridges the gap between them. The members 14 are preferably mounted so as to be adjustable toward and from each other to vary the width of such gap and therefore to regulate the extent to which the periphery of the toplift may project between them to be operated upon by the cutter. For this purpose the tread block 13 is provided with dovetail formations to receive corresponding formations on the members 14, the latter being thus rendered capable of vertical adjustment. The drawings include a convenient form of adjusting means comprising a screw member 15 having a right-hand screw-thread at its lower end to adjust the lower member 14, and having a left-hand screw-thread at its upper end for adjusting the upper member 14. Endwise movement of the screw member is prevented by a pin 16 set in the member 13 in tangential relation to a concentric groove 17 formed in the shank of the screw member. The screw member is shown as having a knurled head at its upper end so that it may be turned with the fingers. Under some conditions it might be desirable to adjust the members 14 so closely one to another as to maintain the periphery of the toplift out of the field of operation of the shaving cutter, but when trimming a heel having an inclined profile calling for a beveled toplift the members 14 may be separated far enough to permit the toplift to extend through the gap so as to partake of the shaving operation while the shaving cutter is shaping the body of the heel.

Furthermore, the toplift guard, including the three members 13, 14, 14, may be adjusted as an entirety toward and from the axis of the cutter. For this purpose the member 13 is provided with a dovetail formation 18 arranged to slide in a correspondingly shaped portion of a bracket 19. Adjustment of the latter kind may be made by turning a thumb-screw 20 the screw-threaded portion of which engages a portion of the bracket 19.

The bracket 19 is movably supported by a regulatable mechanism adapted to shift the toplift guard lengthwise of the profile of the shaving cutter during the process of shaving a heel, the regulatable construction being adapted to shape the path of movement of the toplift guard to conform to the profile of the shaving cutter, whatever form said profile may have within the limits of the range traversed by said guard. As shown the bracket 19 is fastened to a link 21 by a clamping bolt 22 preferably supplemented by suitable tongue-and-groove formations on the members 19 and 21 respectively to prevent the member 19 from turning about the bolt. The clamping bolt extends through a slot 30 in the bracket, which slot affords a considerable range of horizontal adjustment of the toplift guard relatively to the link 21. For the purpose of effecting horizontal adjustments of the bracket the latter is provided with a rack 31 and the link 21 is provided with a manually operable pinion 32 engaging said rack. The link 21 is supported by links 23 and 24 to which it is connected by pivot studs 25 and 26 respectively. The link 23 is connected by an anchoring pivot 27 a fixture 28, said fixture having a segmental slot 29 through which the pivot 27 extends and affording a range of adjustment by which said pivot may be located in various positions to modify and determine the path of movement of the toplift guard as aforesaid. The link 24 is preferably made of two relatively adjustable sections by which its effective radius may be increased and decreased to modify the shape of the path traversed by the toplift guard in addition to the modifications afforded by the aforesaid adjustability of the anchoring pivot 27. As shown by Fig. 4 the pivot member 26 is carried by a dovetailed member 33 arranged in a corresponding dovetailed portion of the member 24. The anchoring pivot 34 of the member 24 is fixed to the fixture 28, and the member 33 is adjustable in such a way as to shift the pivot 26 toward and from the axis of the anchoring pivot 34. The effective radius of the link 24 is therefore capable of being varied by adjusting the pivot member 26 toward and from the anchoring pivot 34. For this purpose the member 24 is provided with an adjusting screw 35, and the member 33 is provided with a groove 36 to receive a flange or collar 37 on the screw. To maintain the member 33 in various positions of adjustment the member 24 is split to form two cooperative clamping portions and is provided with a bolt 38 to draw said portions toward each other in such a way as to clamp the member 33.

The range of movement of the toplift guard lengthwise of the profile of the shaving cutter is determined by two adjustable stop screws 39 and 40, the screw 39 serving as

an abutment for a portion 41 of the member 24, and the screw 40 serving as an abutment for an ear 42 formed on the connecting link 21. A torsion spring 43 encircling the anchoring pivot 34 normally urges the toplift guard toward the left and thereby maintains the portion 41 initially against the stop screw 39. Mechanism hereinafter described is provided for actuating the member 24 to shift the toplift guard to the right and also to control its return movement to its initial position. Said mechanism includes a gear segment 44 formed on the member 24 and arranged in meshed relation to a gear segment 45 formed on an arm 46. The description of the mechanism for actuating the arm 46 is postponed relatively to a description of the counter guard because, according to the illustrated organization, both guards receive motion from one source.

The counter guard 47 herein illustrated is cup-shaped and adapted to surround and enclose more or less of the shaving cutters 10. It is supported by a carrier 48 and is rotatable relatively to the carrier so that it may have rolling contact with the counter portion of a shoe or with any alternative templet with which the heel may be provided to govern the shaving at the base end. For example, so far as certain aspects of the invention are concerned it would be within the scope of the invention to trim an unattached heel with the illustrated mechanism. The rotatability of the counter guard not only minimizes the wearing effect of the base templet but distributes such wearing effect around the periphery of the guard so that one portion will not be worn more than others. The carrier 48 is supported by a pair of links 49 and 50 to which it is connected by pivot members 51 and 52. The link 49 is connected to a stationary but adjustable bracket 53 by an anchoring pivot 54, while the link 50 is connected to said bracket by an anchoring pivot 55. The pivot 54 extends through a segmental slot 56 in the bracket which affords a range of adjustment for the purpose of shaping the path of movement of the counter guard to conform to the profile of the cutters. The counter guard may be adjusted transversely of its axis by advancing or retracting the bracket 53, and since the wall of the counter guard is very thin its periphery may be adjusted very closely to the periphery of the cutters without interference. Although Fig. 1 shows a counter guard in substantially concentric relation to the cutter-head actual working conditions would require a closer relation between the work-engaging portion of the guard and the cutters. The desired relation would be established by turning the adjusting screw 57 which has screw engagement with a clamping portion 58 of the bracket. This clamping portion has tongue-and-groove engage-

ment with two cooperative clamping portions 59 of a carriage 60, said clamping portions being provided with a clamping bolt 61 and an operating member 62 by which they are drawn together to hold the bracket 70 rigidly. The carriage 60 has tongue-and-groove connection with cooperative clamping portions 63 of a fixture that may be fastened to the frame of the machine. An adjusting screw 64 is arranged to adjust the carriage 75 60 relatively to said fixture along lines at right angles to the lines of adjustment effected by the screw 57. These adjusting devices are sufficient to establish any desired normal or initial position of the counter 80 guard according to the style of cutter and according to the style of heel to be shaped.

An arm 65 is rigidly connected to the link 50 so that these two elements constitute a two-arm lever, the connection being formed by the anchoring pivot 55 to which the link 50 is pinned or otherwise permanently fixed and to which the arm 65 is clamped by a bolt 66. Motion is transmitted to the arm 65 by a link 67, lever 68 and link 69 from an operating lever 70. The link 67 is provided with a slot 71 and the connection between this link and the arm 65 is formed by a bolt 74 and collar 73 which, under certain conditions, may be tightened to clamp the link 95 against a swiveled piece 72 (Fig. 6), and under other conditions may be loosened to permit lost motion of the link. When lost motion is desired its amplitude may be regulated by a stop-screw 94 carried by the link. This screw is arranged to abut against the piece 72 for the purpose of transmitting motion of the link to the arm 65. The other end of the link 67 is adjustably connected to the arm 68 by cooperative clamping members which provide pivotal connection, one of said clamping members being a bolt 75 and the other being a pivot stud having a circular head or flange arranged in an undercut groove 95 in the lever 68. The fulcrum stud 100 of the lever 68 is indicated at 76. By loosening the bolt 66 the arm 65 may be turned around about 180 degrees relatively to the link 50 to provide for reversing the direction 105 of movement of the counter guard relatively to that of the toplift guard.

The counter guard is urged toward the toplift guard at all times by a spring 96, and its limit of motion in that direction is determined by an adjustable screw 97 and a stop 98. The stop is formed on the stationary bracket 53, and the screw is carried by the link 50.

Owing to the fact that the operating lever 70 is arranged to swing about an axis that is not parallel to that of the fulcrum stud 76 universal joints 77 are provided to connect the link 69 with the levers 68 and 70. These connections are represented as of the ball-and-socket type.

The invention is not limited as to any particular means for actuating the lever 70, but the illustrated embodiment of the invention includes a treadle 78 for this purpose (see Fig. 6). The lower end of an operating rod 79 is pivotally connected to the treadle, and the upper end is pivotally connected to the lever 70 by a pin 80. A strong spring 81 normally raises the treadle and the rod 79 to maintain the parts in the positions shown by Figs. 1, 4 and 6. The lever 70 is formed to straddle the cutter shaft 11 and is mounted on two coaxial fulcrum members 82 and 83.

Referring to Fig. 1, when the treadle is moved downwardly the link 69 moves from right to left, thereby transmitting motion to the lever 68 from which it is transmitted to the counter guard to move the latter from right to left with variable amplitude according to the lost-motion connection at 71 and according to the position at which the pivotal connection 75 is adjusted. For example, if this pivot connection is at a relatively great distance from the axis of the fulcrum 76, the link 67 will receive relatively great amplitude of movement, and if the screw 94 is set to provide lost motion the movement of the counter guard will not begin until after the toplift guard has been shifted. Furthermore, if the position of the arm 65 is reversed the counter guard will move in the same direction as the toplift guard. The lever 68 may have a constant range of movement of any desired amplitude while the amplitude of motion transmitted to the counter guard from said lever may be regulated as desired by shifting the point of pivotal connection between said lever and the link 67.

The lever 68 may serve also to transmit motion to the toplift guard so that the motions of the two guards may be synchronized. For this purpose the illustrated mechanism is so organized that the segment arm 46 will swing about the same axis as the lever 68. In fact, the fulcrum member 76 extends through the arm 46 so as to serve as the fulcrum member for this arm as well as for the lever 68. The connection is preferably such as to enable the lever 68, under certain conditions, to swing without imparting any movement to the arm 46. A yieldable connection is formed between the lever 68 and the arm 46 by a spring 84, one end of said spring being seated in a socket formed in an adjustable screw 85 carried by the lever 68 while the other end of said spring is seated in a socket formed in the arm 46. The arm 46 and the lever 68 are provided with bosses 86 and 87 arranged to abut one against the other and normally held in abutting relation by the spring, and the latter serves as a yielding transmission medium to move the toplift guard from left to right. The yielding connection afforded by the spring 84 per-

mits shifting the counter guard irrespective of the extent to which the toplift guard is permitted to move by its arresting screw 40. In fact, if the screws 39 and 40 are set so as to hold the toplift guard positively in one position, the fixed condition of the toplift guard will not interfere with the shifting of the counter guard. Further, if the work is such that it would be desirable to shift both guards simultaneously at first and to continue the shifting of the counter guard after arresting the toplift guard, the arresting screw 40 would be adjusted to determine the desired limit of movement of the toplift guard and would determine the point at which the arm 46 would cease to move in unison with the lever 68. Beyond this point the spring 84 would yield to permit a continuation of the shifting movement of the counter guard. Then, as the mechanism returns to its normal position, the toplift guard would remain stationary against its arresting screw 40 until the boss 87 strikes the boss 86, and thereafter the two guards would move simultaneously to their initial positions. These results are illustrated diagrammatically by Fig. 2 in which the normal positions of the various movable elements are indicated by broken lines A, the position at which the toplift guard is arrested are indicated by continuous lines B, and the ultimate positions corresponding to the extreme position of the counter guard are indicated by broken lines C. Furthermore, the corresponding positions of the centers of certain pivots and their ranges of motion are indicated by corresponding lines and letters of reference. For example, the operating link 69 is shown in three successive positions, A representing its normal position, B representing its position at which the toplift guard is arrested, and C representing the extent to which it may be moved after the toplift guard has been arrested. It follows, therefore, that the toplift guard will move from position A to position B while the lever 68 is moving from position A to position B, the counter guard also moving simultaneously from position A to position B. During this stage of shifting, the pivots 25 and 26 will swing from positions A to positions B and thus shape the path of movement of the toplift guard as desired. While the lever 68 moves from B to C it will shift the counter guard from B to C but the toplift guard will be detained at B by the stop 40.

Under the conditions of regulation explained in the last paragraph the two guards may be shifted simultaneously while trimming along the sides of a heel between lines A and B as applied to Fig. 7, line B, as before, representing the point at which the toplift guard would be arrested. The shifting of the toplift guard not only compensates to some extent for the wedge factor of the heel, but

also varies the distance between the highest point of the cutter and the toplift so that the highest point of the cutter will be led along the heel substantially as indicated by 5 broken line 100. This avoids cutting too deeply into the waist of the heel. In shaving the back of the heel from line B on one side to line B on the opposite side the toplift guard may remain stationary while the 10 counter guard continues to move out and then back to compensate further for the wedge factor.

Another variation can be had by using the 15 lost motion connection at 71 (Figs. 1 and 2) so as to postpone the movement of the counter guard until the toplift guard has been arrested (on the out-stroke) and to arrest the return motion of the counter guard at the point where the return motion of the 20 toplift guard begins. For example, while the lever 68 moves from A to B it would move the toplift guard only; in moving from B to C and back to B the counter guard would move out and back to its 25 arresting member 98; then the lever and toplift guard would return from B to A.

For such styles of wedge heels as would 30 not require arresting the toplift guard during the shifting of the counter guard, the shifting of the guards would progress as 35 represented diagrammatically by Fig. 3. Here three outlines of a heel are represented and are numbered 1, 2 and 3 respectively. Outline 1 represents the outline of the front 40 part of the heel, outline 2 represents the outline at the widest part, and outline 3 represents a side elevation, each of the final form. The correspondingly numbered lines intersecting the profile of the cutter indicate 45 corresponding positions of the toplift guard and counter guard as the guards are moved along the length of said profile, and the arrow-head lines 1, 2 and 3 within the outline of the cutter indicate the ranges of the cutter that function at the corresponding stages of shaping.

In connection with Fig. 3 it may be observed 50 that the toplift 88 partakes of the trimming action of the cutter so that the desired profile is imparted to the heel throughout its entire height at all stages of shaping. The capacity of the mechanism thus to produce the desired profile in the toplift while imparting such profile to the body 55 and wedge portions is made possible by that feature of construction hereinbefore described which enables the cutter to operate on the toplift between the two abutments 14. These abutments may be so adjusted 60 that the cutter will intersect the edge formed by the tread surface and periphery of the toplift, in which case the cutter will trim the entire thickness of the toplift without changing the contour of the tread surface. 65

It has been stated that the path of move-

ment of the toplift guard may be shaped to conform to the periphery of the cutter by regulating the links 23 and 24, and while this is true there may be occasions when even better results could be obtained by 70 regulating said links so as to produce a slight variation between the path of the toplift guard and the profile of the cutter. For example, since the two-point bearing of the toplift on the abutments 14 will enable 75 portions of relatively pronounced curvature to extend through the gap and into the field of trimming to a greater extent than portions of less curvature, the depth of trimming would be greater at the points of pronounced curvature than at the points of less curvature, and to this extent, which, obviously, would necessarily be slight, the contour of the toplift might not be fully preserved in the absence of some compensatory factor. Now, therefore, if the links 23 and 20 be regulated to advance the work toward the cutter when the portions of relatively slight curvature are bearing thereon and to 80 retract the work slightly when the portions of relatively pronounced curvature are bearing thereon, and if the degree of such regulation be substantially commensurate with the variations of curvature in the periphery of the toplift, the path of movement of 85 the toplift guard will be almost, but not quite, parallel to the contour of the cutter and the result will be a practically perfect job of trimming. This compensatory factor may be utilized in every case regardless 90 of whether the heel has or has not a wedge formation. If it has no wedge formation or too little to take up the increase of space between the guards when the toplift guard is moved to produce such compensatory factor the desired relation between the two guards may be maintained by swinging the arm 65 to the opposite side of the axis of 95 the fulcrum 55. Then the guards will be caused to move in the same direction at the 100 same time, the follow-up movement of the counter guard serving to maintain the desired distance between the guards while the 105 toplift guard is moving to produce the aforesaid compensatory effect.

In all machines for shaping heels as to 110 which the work is held and manipulated by the operative it is necessary to provide a heel rest to maintain the work in the desired 115 relation to the cutter and to sustain the cutting stress. Such a heel rest is arranged to bear against the periphery of the heel so that the latter may rock on it. It has been customary heretofore to fix such a heel rest in one position, but for the purpose of trimming heels according to the present invention it is desirable to have it moved laterally 120 with the toplift guard. Accordingly the drawings include a heel rest 89 that is arranged to move in unison with the toplift 125 130

guard so as to remain in a constant relation thereto. According to the illustrated construction of this feature the heel rest is formed with a cylindric shank 90 (Fig. 5) 5 and said shank is adjustably held by a split clamping portion 91 of a holder having a cylindric shank portion 92 extending at right angles to the shank 90. The shank 92 is adjustably held by a split clamping portion 93 of the bracket 19 that carries the top-lift guard. The holder 91, 92 is adjustable lengthwise of its shank portion and rotatively, while the heel rest is also adjustable lengthwise of its shank portion and also 10 rotatably. Collectively these provisions for adjustment permit setting the heel rest at any position best suited to the size and style of heel to be shaped.

Having thus described my invention, what 20 I claim as new and desire to secure by Letters Patent of the United States is:

1. A heel-trimming machine comprising a rotary cutter profiled to impart substantially the final shape to a heel, a counter guard and 25 a top-lift guard arranged for relative movement toward and from each other, and mechanism constructed and arranged to effect said relative movement of the guards toward or from each other during the operation 30 of trimming a heel.

2. A heel-shaping machine comprising a mechanically operated cutter having a profile adapted to shave the periphery of the heel to substantially final shape, means arranged to control the pitch and course of such shaving by engaging the counter and toplift of the shoe to which the heel is attached, and mechanism arranged to shift said controlling means so as to cover and uncover 35 portions of said cutter during the operation of shaving the heel.

3. A heel-shaping machine comprising a mechanically operated cutter arranged to shave the periphery of a heel, means arranged to control the pitch and course of such shaving by engaging the toplift and counter of the shoe to which the heel is attached, and mechanism arranged to shift said controlling means so as to cover and uncover 40 portions of the cutter during the shaving operation, the cutter being formed and arranged to impart substantially final shape to the body and wedge portions of a wedge heel.

4. A heel-shaping machine comprising a mechanically operated cutter arranged to shave the periphery of a heel, means arranged to control the pitch and course of such shaving by engaging the periphery of the toplift at separate points and the counter of the shoe to which the heel is attached, and mechanism arranged to shift said controlling means so as to cover and uncover portions of the cutter during the shaving operation, said cutter being formed and arranged to 45

operate on the toplift between said separate points and to impart substantially final shape to the toplift and the body of the heel simultaneously.

5. A heel-shaping machine comprising a 70 mechanically operated cutter arranged to shave the periphery of a heel, means arranged to control the pitch and course of such shaving by engaging the toplift and counter of a shoe to which the heel is attached, and mechanism arranged to shift said controlling means so as to cover and uncover portions of the cutter during the shaving operation and to regulate the range of the uncovered portion according to variations 75 in the height of a wedge heel, said controlling means being arranged to afford access of the entire thickness of the toplift to the cutter, and the cutter being formed and arranged to impart substantially final shape 80 to the body and wedge portions while trimming the toplift.

6. A heel-shaping machine comprising a mechanically operated cutter arranged to shave the periphery of a heel, a counter 90 guard and a toplift guard one of which is movable toward and from the other, and mechanism arranged to move said movable one of the guards toward and from the other during the operation of shaving a heel. 95

7. A heel-shaping machine comprising a mechanically operated cutter arranged to shave the periphery of a heel, a counter guard, a toplift guard movable toward and 100 from the counter guard, mechanism arranged to move the toplift guard in one of said directions during the operation of shaving a heel, and a spring arranged to move said toplift in the other one of said directions. 105

8. A heel-shaping machine comprising a mechanically operated cutter arranged to shave the periphery of a heel, a toplift guard, a counter guard movable toward and from the toplift guard, and mechanism arranged to move the counter guard toward 110 and from the toplift guard during the operation of shaving a heel.

9. A heel-shaping machine comprising a mechanically operated cutter arranged to shave the periphery of a heel, a counter guard and a toplift guard each movable toward and from the other, and mechanism arranged to move said guards toward and from each other during the operation of 115 shaping a heel.

10. A heel-shaping machine comprising a mechanically operated cutter arranged to shave the periphery of a heel, a movable counter guard, a movable toplift guard, and mechanism arranged to move said guards with unequal amplitudes of movement. 125

11. A heel-shaping machine comprising a mechanically operated cutter arranged to shave the periphery of a heel, a movable 130

counter guard, a movable toplift guard, and mechanism arranged to move said guards in different directions.

12. A heel-shaping machine comprising a mechanically operated cutter arranged to shave the periphery of a heel, a movable counter guard, a movable toplift guard, and mechanism connecting said guards so that movement imparted to one will be communicated to the other.

13. A heel-shaping machine comprising a mechanically operated cutter arranged to shave the periphery of a heel, a counter guard and a toplift guard each movable toward and from the other, and mechanism arranged to move said guards simultaneously in opposite directions.

14. A heel-shaping machine comprising a mechanically operated cutter arranged to shave the periphery of a heel, a movable counter guard, a movable toplift guard, and regulatable mechanism arranged to move said guards along variable lines.

15. A heel-shaping machine comprising a mechanically operated cutter arranged to shave the periphery of a heel, a movable counter guard, a movable toplift guard, means arranged to arrest movement of one of said guards, and mechanism arranged to move the latter said one of said guards against its said arresting means and to move the other one of said guards while the arrested guard remains against said arresting means.

16. A heel-shaping machine comprising a mechanically operated cutter arranged to shave the periphery of a heel, a movable counter guard, a movable toplift guard, means arranged to arrest movement of one of said guards, and mechanism arranged to move said guards simultaneously and to continue the movement of the other one after the one having said arresting means is arrested thereby.

17. A heel-shaping machine comprising a mechanically operated cutter arranged to shave the periphery of a heel, a movable counter guard, a movable toplift guard, mechanism arranged to move one or both of said guards according to whether the other guard is restrained from moving, and means arranged to keep said other guard in one position during a part only of the movement of the said one of said guards.

18. A heel-shaping machine comprising a mechanically operated cutter arranged to shave the periphery of a heel, a movable counter guard, a movable toplift guard, and mechanism arranged to move said guards simultaneously but including a yieldable connection with one of them so that it may actuate the other when said one is arrested.

19. A heel-shaping machine comprising a mechanically operated cutter arranged to shave the periphery of a heel, a movable

counter guard, a movable toplift guard, and mechanism arranged to move said guards and including means for relatively varying the proportions of movement impartable by it to the guards

20. A heel-shaping machine comprising a mechanically operated cutter arranged to shave the periphery of a heel, a movable counter guard, a movable toplift guard, actuating means arranged to move one of said guards while a shaving operation is in progress, and regulatable mechanism arranged to transmit motion from said actuating means to the other one of said guards, said mechanism being regulatable to vary the amplitude of motion imparted to said other one relatively to that of said actuating means

21. A heel-shaping machine comprising a mechanically operated cutter arranged to shave the periphery of a heel, a counter guard, a movable toplift guard, and regulatable mechanism arranged to move said toplift guard along predetermined variable lines toward and from the counter guard.

22. A heel-shaping machine comprising a mechanically operated cutter arranged to shave the periphery of a heel, a toplift guard, a counter guard, and regulatable mechanism arranged to move the counter guard along predetermined variable lines toward and from the toplift guard.

23. A heel-shaping machine comprising a mechanically operated cutter arranged to shave the periphery of a heel, a counter guard, a movable toplift guard, and mechanism arranged to move said toplift guard along a curvilinear course toward and from the counter guard.

24. A heel-shaping machine comprising a mechanically operated cutter arranged to shave the periphery of a heel, a toplift guard, a movable counter guard, and mechanism arranged to move said counter guard along a curvilinear course toward and from the toplift guard.

25. A heel-shaping machine comprising a mechanically operated cutter arranged to shave the periphery of a heel, a movable counter guard, a movable toplift guard, and mechanism arranged to move said guards along curvilinear courses toward and from each other.

26. A heel-shaping machine comprising a mechanically operated cutter arranged to shave the periphery of a heel, a movable counter guard, a movable toplift guard, and mechanism arranged to move said guards simultaneously along curvilinear courses.

27. A heel-shaping machine comprising a mechanically operated cutter arranged to shave the periphery of a heel, a movable counter guard, a movable toplift guard, and regulatable mechanism arranged to move said guards and being regulatable to vary

the amplitude of movement imparted to one without varying that imparted to the other.

28. A heel-shaping machine comprising a mechanically operated cutter arranged to shave the periphery of a heel, a movable counter guard, a movable toplift guard, and regulatable mechanism arranged to move said guards but being regulatable to maintain one of the guards in one position while operating to move the other.

29. A heel-shaping machine comprising a mechanically operated cutter arranged to shave the periphery of a heel, a movable counter guard, a movable toplift guard, and regulatable mechanism arranged to move said guards and being regulatable to reverse the direction of movement of one of them.

30. A heel-shaping machine comprising a mechanically operated cutter arranged to shave the periphery of a heel, a movable counter guard, a movable toplift guard, and regulatable mechanism arranged to move said guards and being regulatable to vary the lines of movement of one of them.

31. A heel-shaping machine comprising a mechanically operated cutter arranged to shave the periphery of a heel, a movable counter guard, a movable toplift guard, and regulatable mechanism arranged to move said guards and being regulatable to vary the lines of movement of each of them independently of the other.

32. A heel-shaping machine comprising a mechanically operated cutter arranged to shave the periphery of a heel, a counter guard, a toplift guard movable toward and from said counter guard to cover and uncover portions of said cutter, and mechanism arranged to control the movements of said toplift guard toward and from the counter guard.

33. In a heel-shaping machine, the combination with a mechanically operated shaving cutter, of a movable counter guard, regulatable means adapted to shape the path of movement of said guard according to the profile of the corresponding range of said cutter, a movable toplift guard, and regulatable means adapted to shape the path of movement of the toplift guard according to the profile of its corresponding range of said cutter.

34. In a heel-shaping machine, the combination with a mechanically operated shaving cutter, of a movable toplift guard, and regulatable means adapted to shape the path of movement of said guard according to the profile of the corresponding range of said cutter.

35. In a heel-shaping machine, the combination with a mechanically operated shaving cutter, of a movable counter guard, a movable toplift guard, regulatable means adapted to shape the path of movement of said toplift guard according to the profile

of the corresponding range of said cutter, and mechanism arranged to move said guards so as to vary the effective range of the cutter while the latter is shaving a heel.

36. In a heel-shaping machine, the combination with a mechanically operated shaving cutter, of a movable counter guard, regulatable means adapted to shape the path of movement of said guard, a movable toplift guard, regulatable means adapted to shape the path of movement of said toplift guard, and regulatable mechanism arranged to move said guards through ranges of variable but predetermined amplitude.

37. In a heel-shaping machine, the combination with a mechanically operated shaving cutter, of a counter guard and a toplift guard each movable to cover and uncover parts of the cutter, regulatable mechanism arranged to move one of said guards to and fro through a range of variable but predetermined amplitude, and yieldable means operable by said mechanism to move the other one of said guards.

38. A heel-shaping machine comprising a mechanically operated cutter arranged to shave the periphery of a heel, a counter guard, and a toplift guard including a tread rest and two separate abutments in contiguous relation thereto, said abutments being arranged to cover working portions of the cutter and to bear simultaneously on the periphery of the toplift to determine a course of trimming according to the contour of the toplift and to enable said periphery to extend into the field of trimming between them.

39. A heel-shaping machine comprising a mechanically operated cutter arranged to shave the periphery of a heel, a counter guard, and a toplift guard including a tread rest and two separate abutments arranged to bear simultaneously on the periphery of the toplift to determine a course of trimming according to the contour of the toplift and to enable said periphery to extend into the field of shaving between them, said abutments being adjustable toward and from each other in parallel lines to regulate the depth of shaving.

40. A heel-shaping machine comprising a mechanically operated cutter arranged to shave the periphery of a heel, a counter guard, an adjustable tread rest, and two separate abutments carried by said tread rest, the work-engaging faces of said abutments and tread rest forming angles to receive the edge of the toplift, and said abutments being arranged to bear simultaneously on the periphery of the toplift so as to determine a course of shaving and to provide a gap through which said periphery may extend to partake of the shaving action of said cutter.

41. A heel-shaping machine comprising a mechanically operated cutter arranged to shave the periphery of a heel, a counter guard, an adjustable tread rest, two separate abutments carried by said tread rest to bear simultaneously on the periphery of the toplift so as to determine a course of shaving and to provide a gap through which said periphery may extend to partake of the shaving action of said cutter and adjusting means connecting said abutments to adjust them toward and from each other so that the width of said gap and the depth of shaving may be regulated.
42. A heel-shaping machine comprising a mechanically operated cutter arranged to shave the periphery of a heel, a counter guard, an adjustable tread rest, two separate abutments carried by said tread rest to bear simultaneously on the periphery of the toplift so as to determine a course of shaving and to provide a gap through which said periphery may extend to partake of the shaving action of said cutter, and means carried by said tread rest for simultaneously adjusting said abutments toward or from each other to regulate the depth of shaving.
43. A heel-shaping machine comprising a mechanically operated cutter arranged to shave the periphery of a heel, a counter guard, a toplift guard movable toward and from said counter guard to cover and uncover portions of said cutter, said toplift guard having two separate abutments arranged to bear simultaneously on the periphery of the toplift to determine a course of shaving and to provide a gap through which said periphery may extend to partake of the shaving action of said cutter, and means for moving said toplift guard while a shaping operation is in progress.
44. In a heel-shaping machine, the combination with a mechanically operated shaving cutter, of a toplift guard having two separate abutments arranged to bear simultaneously on the periphery of the toplift to determine the depth of shaving, said guard being movable in lines substantially parallel to the profile of said cutter while a shaping operation is in progress to cover and uncover portions of the cutter, and said abutments being arranged to form a gap through which said periphery may extend to partake of the shaving action of the cutter.
45. In a heel-shaping machine, the combination with a mechanically operated shaving cutter, of a movable toplift guard having two separate abutments arranged to bear simultaneously on the periphery of the toplift to determine a course of shaving and to form a gap through which said periphery may extend to partake of the shaving action of said cutter, and regulatable means adapted to shape the path of movement of said guard according to the profile of the corresponding range of said cutter.
46. In a heel-shaping machine, the combination with a mechanically operated shaving cutter, of a movable toplift guard, and two cooperative links pivotally connected to said guard to determine its path of movement and having relatively adjustable anchoring pivots, one of said links comprising relatively adjustable sections by which the length of its effective radius may be changed to modify the path of movement of said guard.
47. A heel-shaping machine comprising a mechanically operated shaving cutter, a counter guard, a movable toplift guard, a controller movable by the operative at will, and means operable by said controller for moving said toplift guard lengthwise of the profile of said cutter while said cutter is shaving a heel.
48. A heel-shaping machine comprising a mechanically operated shaving cutter, a toplift guard, a movable counter guard, a controller movable by the operative at will, and means operable by said controller for moving said counter guard while said cutter is shaving a heel.
49. A heel-shaping machine comprising a mechanically operated shaving cutter, a movable counter guard, a movable toplift guard, a controller movable by the operative at will, and means operable by said controller for moving said guards while said cutter is shaving a heel.
50. A heel-shaping machine comprising a mechanically operated cutter for shaving the periphery of the heel to substantially final shape, a counter guard and a toplift guard one of which is movable toward and from the other to cover and uncover parts of said cutter, manually operable means arranged to move said movable guard in one direction, and a spring arranged to move it in the opposite direction.
51. A heel-shaping machine comprising a mechanically operated cutter for shaving the periphery of the heel to substantially final shape, a counter guard and a toplift guard one of which is movable toward and from the other to cover and uncover parts of said cutter, a spring arranged to move said movable guard in one direction, and other means arranged to move it in the opposite direction.
52. A heel-shaving machine comprising a mechanically operated cutter for shaving the periphery of a heel to substantially final shape, a movable counter guard, a movable toplift guard, spring-stressed mechanism arranged to move said guards normally to predetermined positions, and means arranged to actuate said mechanism so as to move the guards away from said positions while said cutter is shaving a heel.

53. A heel-shaping machine comprising a mechanically operated cutter arranged to shave the periphery of an attached heel, and means relatively to which the heel is movable 5 constructed and arranged to engage the counter of the shoe and the toplift so as to control the depth of shaving and to permit said cutter to shave the entire thickness of the toplift while shaving the body of the 10 heel.
54. A heel-shaping machine comprising a mechanically operated cutter arranged to shave the periphery of a heel, a movable counter guard, a movable toplift guard, and 15 mechanism arranged to move said guards and including a lost-motion connection by which the movement of one of them may be postponed to begin after the other one has been moved thereby.
55. A heel-shaping machine comprising a mechanically operated cutter arranged to shave the periphery of a heel, a movable counter guard, a movable toplift guard, and 20 manually operable means arranged to move 25 said guards simultaneously.
56. A heel-shaping machine comprising a mechanically operated cutter arranged to shave the periphery of a heel, a movable counter guard, a movable toplift guard, a 30 treadle, and connections from said treadle to 35 said guards to shift the latter to and fro.
57. A heel-shaping machine comprising a mechanically operated cutter adapted to shave the periphery of a wedge heel to substantially final shape, a movable counter 40 guard and a movable toplift guard arranged to control the pitch and course of shaving, and mechanism arranged to move said 45 guards and adapted to coordinate their movements according to the following cycle, viz., a movement of the toplift guard away from the counter guard, a movement of the counter guard away from the toplift guard, a movement of the counter guard toward 50 the toplift guard, and a movement of the toplift guard toward the counter guard.
58. That improvement in methods of shaping a wedge heel which consists in generating a predetermined profile progressively 55 around the periphery of the heel by shaving the entire thickness of the body and wedge portions simultaneously to such profile, and controlling the pitch of the generated profile and the depth of such shaving according to predetermined standards so that a single course of shaving will impart the final shape to the periphery.
59. That improvement in methods of shaping a wedge heel which consists in generating a predetermined profile progressively 60 around the periphery of the heel by shaving the entire thickness of the body and portions simultaneously to such profile, controlling the pitch of the profile and limiting the depth of shaving to final predetermined 65 standards in the first instance, and leading the generated profile otherwise than parallel to the plane of the top of the heel with a component of relative shifting movement in a direction lengthwise of the profile as the 70 shaping progresses.
60. That improvement in methods of shaping an attached heel having a toplift of substantially final contour which consists in shaving the body of the heel and the toplift 75 to a predetermined profile and at the same time controlling the pitch and course of shaving partly by a point of bearing on the counter and partly by two points of bearing in tandem relation on the periphery of the top- 80 lift.
61. That improvement in methods of shaping an attached heel having a toplift of substantially final contour, which consists in shaving the body of the heel and the toplift 85 simultaneously to a predetermined profile and at the same time controlling the pitch and course of shaving partly by the periphery of the toplift and partly by the counter 90 of the shoe.
62. That improvement in methods of shaping an attached heel having a toplift of substantially final contour, which consists in shaving the body of the heel and the entire 95 thickness of the toplift simultaneously to a predetermined profile and at the same time controlling the course of such shaving by physical contact with the counter of the shoe and the periphery of the toplift.
63. That improvement in methods of shaping a heel having a toplift of substantially final contour, which consists in shaving the body of the heel to a predetermined profile and at the same time controlling the course 100 of such shaving by a point on the counter and two separate points in tandem relation on the periphery of the toplift, and simultaneously shaving said periphery between said 105 points.
64. That improvement in methods of shaping a wedge heel having a toplift of substantially final contour, which consists in shaving the body and wedge portions of the heel simultaneously to a predetermined profile and at the same time controlling the course and pitch of such shaving partly by the periphery of the toplift.
65. That improvement in methods of shaping a wedge heel having a toplift of substantially final contour, which consists in shaving the body and wedge portions of the heel simultaneously to a predetermined profile and at the same time controlling the course and pitch of such shaving partly by two 110 separate points in tandem relation on the periphery of the toplift, and simultaneously shaving said periphery between said points.
66. That improvement in methods of shaping a wedge heel having a toplift of substantially final contour, which consists in shav- 115
- 65 120
- 65 125
- 65 130

ing the toplift, heel body and wedge portion simultaneously to a predetermined profile, and at the same time controlling the pitch and course of such shaving partly by the periphery of the toplift.

67. That improvement in methods of shaping a wedge heel having templets fixed adjacent to its top and bottom surfaces, which consists in shaving the body and wedge por-

tions simultaneously to final form, causing such shaving to progress around the periphery of the heel, and at the same time controlling the course and pitch of such shaving by said templets.

In testimony whereof I have signed my name to this specification.

FRANK ANTON EICH.
